UNITED STATES PATENT OFFICE.

IRVING I. KREMER, OF NEW YORK, N. Y.

NON-REFILLABLE BOTTLE.

No. 874,211.

Specification of Letters Patent.

Patented Dec. 17, 1907.

Application filed September 27, 1907. Serial No. 394,832.

To all whom it may concern:

Be it known that I, IRVING I. KREMER, a citizen of the United States, and a resident of the city of New York, borough of Manhattan, in the county and State of New York, have invented a new and Improved Non-Refillable Bottle, of which the following is a full, clear, and exact description.

This invention relates to certain improvements in bottles, and more particularly to means whereby a bottle which has once been emptied cannot be refilled.

The essential feature of the construction involves a valve having a substantially hemispherical seating portion and an oscillating portion extending therefrom, and so constructed that the last-mentioned portion may be oscillated as the bottle is inclined, without moving the valve from its seat until after the bottle has been inclined to a predetermined distance.

Reference is to be had to the accompanying drawings, forming a part of this specification, in which similar characters of reference indicate corresponding parts in both the figures, and in which

Figure 1 is a longitudinal section through a bottle constructed in accordance with my invention; and Fig. 2 is a perspective view of 30 the bottle valve.

In the specific form illustrated, the bottle neck 10 is provided with an inwardly-directed flange 11 supporting an outwardly-extending ridge 12. The face of the flange 15 together with the ridge, forms the valve seat, and the ridge also serves to retain in position a spacing member 13 hereinafter described. The valve includes a substantially hemispherical portion 14 and a conical oscillatory portion 15 preferably integral therewith. The oscillatory portion is in the form of a truncated cone, the base of the cone fitting the flat surface of the hemispherical portion and the outer end of the cone being provided 45 with a recess 16. Above the valve there is provided a plug 17 having a sinuous passage 18 therethrough, the curvature of the passage being such that the insertion of an instrument or wire to unseat the valve is rendered difficult, if not impossible. The plug 50 rests against the outer end of the annular spacing member 13 which limits its inward movement, and the plug is prevented from withdrawal by a suitable locking means. 55 Preferably, this locking means includes two annular grooves, one in the plug 17 and the

other in the neck of the bottle, one of the grooves being adapted for the reception of a series of small balls 19, while the plug is being inserted, and the two grooves co-operating 60 with the balls to positively prevent the plug from being withdrawn after the two grooves are brought into registry. This form of locking means is old and well-known in the art, and as it forms no part of the present invention, it is evident that other locking means may, if desired, be employed in place thereof. The plug 17 carries a downwardly-extending projection 20 adapted to enter the recess 16 of the valve, but normally out of 70 engagement with the valve proper. The projection is somewhat less in cross section than is the recess, and the projection does not extend to the bottom thereof. The projection as illustrated, is integral with the 75 plug 17, but it is evident that it may be carried by a separate member if desired.

In the operation of the device the bottle is filled before the valve and plug are inserted. The valve is then dropped upon its seat and 80 the plug carrying the balls 19 is inserted until the balls enter the annular groove in the bottle neck. Upon inverting the bottle, the valve leaves its seat and drops into engagement with the projection 20, thus permitting 85 the liquid to freely flow from the bottle. The center of gravity of the valve is very low, and, therefore, as the valve is being inclined it may move upon its seat to bring one edge of the recess into engagement with the projection 20. Thus the valve is not opened until after the bottle has been inclined to 90 such an extent as to bring the center of gravity to one side of the valve seat. Whichever direction the bottle is inclined, the valve 95 will endeavor to right itself until the edge of the recess engages with the projection and thus delays the time of opening of the valve to a considerable extent. Any attempt to insert a liquid under pressure into the bottle 100 would immediately force the valve to its seat and close the opening.

Having thus described my invention, I claim as new and desire to secure by Letters Patent:

1. In a non-refillable bottle, the combination of a bottle neck presenting an annular valve seat, a valve seated thereon and having a hemispherical body and an oscillating portion extending therefrom, and means for engaging with said oscillating portion to limit its movement.

2. In a non-refillable bottle, the combination of a bottle neck presenting an annular valve seat, a valve seated thereon and having a hemispherical body and an upwardly-extending substantially conical oscillatory portion rigid therewith, and means engaging with said conical portion adjacent its outer end for limiting the oscillations thereof.
3. In a non-refillable bottle, the combination of a bottle neck presenting an annular valve seat, a valve seated thereon and comprising a hemispherical seating portion and an oscillating portion substantially conical in

form and having its outer smaller end provided with a recess, and means for limiting the oscillation of the valve, said means presenting a projection extending into said recess but normally out of engagement with the sides thereof.

In testimony whereof I have signed my name to this specification in the presence of two subscribing witnesses.

IRVING I. KREMER.
